Lighting fixture, especially of the rosette type, having a single disk or hub which is secured in place internally of the fixture and without the use of unsightly locking rings or nuts now commonly used.

UNITED STATES PATENT OFFICE

2,207,408

CEILING AND WALL LIGHTING FIXTURE

William Knapp, Hollis, N. Y.

Application August 12, 1939, Serial No. 289,805

1 Claim. (Cl. 240—85)

This invention relates to ceiling and wall lighting fixtures of the rosette type, and has for one of its objects the provision of a lighting fixture of this character in which the receptacle portion of the fixture is secured in place internally of the fixture and without the use of unsightly locking rings or nuts now commonly used.

Another object of the invention is the provision of a lighting fixture of the nature referred to, comprising a disk preferably made of a plastic material, and provided with a central boss integral with the disk, said boss having a threaded opening which is adapted to receive the threaded end of the receptacle for securing same in place from the rear of the disk.

A further object of the invention is to provide the said boss with a reduced or undercut portion upon which may be supported the globe or lamp shade holder.

20 A still further object of the invention is the provision of means for securing the said fixture to the outlet box, said securing means not being visible from the front of the device.

Up to the present time, lighting fixtures of the rosette type were made in the form of a disk having a central perforation through which extended the threaded portion of the receptacle which was held or locked in place by a threaded ring at the front of the fixture. This construction entailed extra parts and labor and the threaded ring would often become loose and seldom if ever matched the color of the disk, thus giving to the fixture an unsightly appearance. To obviate these undesirable features, I have perfected by improved lighting fixture.

Another object is to produce a device of the character described in which the maximum simplicity of construction and operation is secured.

Other objects and advantages will appear as 40 the nature of the improvements is better understood, the invention consisting substantially in the novel arrangement and co-relation of parts herein fully described and illustrated in the accompanying drawings, wherein similar reference 45 characters are used to describe corresponding parts throughout the several views, and then finally pointed out and specifically defined and indicated in the appended claim.

The disclosure made the basis of exemplifying 50 the present inventive concept suggests a practical embodiment thereof, but the invention is not to be restricted to the exact details of this disclosure, and the latter, therefore, is to be understood from an illustrative, rather than a restrictive standpoint.

Many and varied types of lighting fixtures are known and used, and it is not the intention of the present invention to set forth all of the known types, but rather to set forth a simple, inexpensive, rosette type lighting fixture which is secured in place internally of the fixture and which will not tend to come apart.

Another object of the present invention is to provide a lighting fixture of the rosette type which is secured in place internally of the fixture and which will not tend to come apart, and which is of a simple construction, and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

Another object of the present invention is to provide a lighting fixture of the rosette type which is secured in place internally of the fixture and which is easily and quickly assembled.

the fixture securing screws may be hidden from view, thus enhancing the entire appearance of the fixture.

Having described my invention, what I claim as new and desire to secure by Letters Patent is:

- In a lighting fixture, a disc constituting a body and having a concaved inner face bordered by a flat marginal edge, an outwardly projecting neck at the center of said body formed with a bore 5 extending through the body and having its walls threaded from its inner end, ribs upon the inner face of said body extending radially of the body flush with the marginal edge thereof and terminating in spaced relation to the bore of the neck 10 and having concaved inner end faces confronting the bore in spaced relation thereto, openings being formed through the body and the ribs to receive fasteners for securing the body against an outlet box, and an electric lamp receiving receptacle having a base and a threaded lamp-receiving shell extending from the base and screwed into the bore of said neck from the inner end thereof and removably mounting the receptacle base against the central portion of the inner face of the body between and in close proximity to the concaved inner ends of said ribs. 15

WILLIAM KNAPP.
